UNITED STATES PATENT OFFICE.

GEORGE F. ROSE, OF NEW YORK, N. Y.

TYPE-WRITER.

1,189,626.

Specification of Letters Patent.

Patented July 4, 1916.

Application filed October 23, 1911. Serial No. 656,170.

To all whom it may concern:

Be it known that I, GEORGE F. ROSE, a citizen of the United States, residing in the city of New York, borough of Manhattan, county and State of New York, have invented a certain new and useful Type-Writer, of which the following is a specification.

This invention pertains to improvements in typewriters, and relates, more especially, to novel features in the type-bar guide and the ribbon-vibrator.

In typewriters as heretofore constructed, it has been deemed essential that the type-bar guide be either rigidly supported in position or be movable for a slight distance to expose the writing line. In these machines, however, the platen carriage was not removable unless the certain parts of the machine be removed to permit the platen carriage to be taken off. In the type of machine herein illustrated, the platen carriage is removable without necessitating any dismantling of the machine, and a machine of this construction I have described and claimed in my pending application, filed July 11, 1911, Serial No. 637,900. It may be stated, generally speaking, that the main object of removing the platen carriage, as specified, is to enable the machine to be packed compactly for the purpose of facilitating transportation and handling by the user.

In a machine of the ordinary type of the prior art, if the carriage were removed, even by dismantling certain parts thereof, the type-bar guide and ribbon vibrator would project upwardly from the body of the machine, thereby precluding packing the machine compactly, but, also, exposing such parts to injury.

The present invention overcomes the disadvantages specified, and, with these objects in view, embodies a pivoted type-bar guide whereby said guide may be rotated out of its normal upright position.

The invention embodies, further, a ribbon vibrator adapted to be similarly rotated out of its normal position, and, in the preferred form of this particular embodiment of the invention, I associate the vibrator with the type-bar guide, so that the latter serves as the support for said vibrator, and guides its movement.

Other features of the invention, and the

advantages thereof, will appear from the annexed detailed description.

In the accompanying drawings, I have illustrated one practical embodiment of the invention, but the construction shown there- 60 in is to be understood as illustrative, only, and not as defining the limits of the invention.

Figure 1 is a vertical transverse section through a part of a typewriter illustrating 65 the new type-bar guide and ribbon-vibrator in operative relation to the platen carriage, the dotted lines illustrating the said guide and the ribbon-vibrator adjusted to inop- 70 erative positions. Fig. 2 is a vertical sec- 70 tion on an enlarged scale through the guide and the vibrator, illustrating a part of the platen carriage. Fig. 3 is a horizontal sec- 75 tion on an enlarged scale through the guide and the vibrator. Fig. 4 is a perspective 75 view of the guide and the vibrator detached from the machine.

5 is the platen carriage of a typewriter. As shown, this carriage is supported for sliding movement upon a bed plate 6, the latter being adapted for vertical movement with respect to the type bars 7. The working parts of the typewriter are carried by a suitable frame 8, the same embodying a sector 9 to which the type bars are hung, 85 each type bar being actuated by a suitable key lever 10. The foregoing parts are usual in typewriters of the so-called "front strike" type, and certain features of such a machine, more particularly a removable 90 platen carriage and operating mechanism therefor, are disclosed in my prior applica- 95 tion to which reference has been made.

11 is a horizontal supporting bar, the same being pivotally mounted in bearings 95 12 on the machine frame, whereby said bar is mounted for rocking or turning move- 100 ment. This bar carries a member 13 forming the guide for the type bars 7. The bar and the guide are positioned on the frame 105 in front of the platen carriage, and parallel to the guides for said carriage, said guide 13 being arranged at the middle part of the frame so as to lie in the path of the type heads on the type bars 7.

The guide 13 is shown as consisting of a single plate, one end of which is formed into a head 14. The end portion of the plate and the head thereof are slotted at 15, and the edges of the slotted head are bev- 110

eled at 16, whereby the head end of the guide is forked or bifurcated. The plate of said guide 13 is attached rigidly in a suitable way to the supporting bar, so that 5 the guide is rigid with the bar.

17 designates the ribbon-vibrator, the same being slidably fitted to the guide so as to be supported thereby and movable therewith. The vibrator is shown as a plate provided at one end with a series of fingers 18, 19, 20, 21, said plate being provided, also, with clips 22. The vibrator plate is fitted in compact relation to the type-bar guide, and the clips of said vibrator embrace the side edges of the guide, so that the clips operate to retain the vibrator in position upon the guide, while at the same time the clips permit the vibrator to slide upon the guide. The fingers 19, 20 of the 10 vibrator are positioned at the respective sides of the slot 15 in the guide head, and these fingers are substantially out of alignment with the other fingers 18, 21, of the vibrator. Said fingers 18, 21, are provided 15 at their upper ends with flanges 23, the latter overhanging the path of a ribbon (not shown), said ribbon being free to pass through the spaces separating the fingers 18, 19, and 20, 21, and beneath the flanges 23. 20 The slidable vibrator is provided with a depending stem 24, around which is coiled a spring 25, one end of said spring being seated against the lower end portion of the type-bar guide 13. The stem is provided 25 at its lower end with a head 26, upon which is seated the lower end of spring 25, and this head is positioned for frictional contact with a curved member 27. This member is 30 associated with means adapted to be operated by the movement of either of the type bars, whereby the vibrator is thrown upwardly into operative position upon the depression of any one of the key levers. 35

When the supporting bar is in the position shown in full lines in Fig. 1, the type-bar guide is supported fixedly in position by the bar, and the vibrator is depressed by the spring so that the ribbon will occupy a low position relative to the slot in the 40 guide, thereby exposing the writing line on the platen. Upon the depression of a key, the type bar is thrown upwardly in the usual way and the member 27 is lifted for the purpose of raising the vibrator and the ribbon, 45 the spring being compressed. The head of the type bar is thus caused to pass through the slot in the type-bar guide, the latter acting to position the type head accurately with respect to the writing line, thus preserving the alignment. The upward movement of the actuator lifts the ribbon into the path of the type head, but as the type bar falls back, the spring acts promptly to 50 lower the ribbon relative to the fork in the 55 type-bar guide.

In the normal operative relation of the type-bar guide and the ribbon vibrator to the platen carriage, said guide and vibrator extend upwardly from the rockable supporting bar, as a result of which arrangement said guide or the vibrator, or both of these parts, are in the path of some of the parts on the platen carriage so that they are liable to be struck and injured by one or the other of said parts during the operation of withdrawing the platen carriage from the machine frame, *i. e.* by sliding the platen carriage in the direction of its length as disclosed in my prior application to which reference has been made. To overcome this objection, the operator turns the connected guide and the vibrator downwardly and into the out of service position shown in dotted lines in Fig. 1, the supporting bar turning on the bearings afforded by the brackets of the frame, thus disposing the vibrator and the guide into an out of the way or out of service position, so that the carriage can be removed without striking against the guide or the vibrator. Another advantage secured by turning the guide and the vibrator into the out of service position upon removal of the platen carriage is that the guide and the vibrator occupy a compact relation to the other parts of the machine, so that they are not likely to be struck and injured when packing the machine or in transporting and shipping it. When adjusted as described, the head of the stem rides against the curved member 27 so as to compress the spring, the tension of which acts to retain the parts in their adjusted positions. To return the parts again to operative positions, it is necessary only to lift the guide and vibrator to the full line position of Fig. 1, whereupon the tension of the spring is relaxed somewhat, although the spring is still somewhat under tension so that it will act to hold the supporting bar from turning accidentally.

I have not considered it necessary to fully illustrate or describe the ribbon mechanism, or other parts of the machine, for the reason that said mechanism and parts are not of the present invention.

Having thus fully described the invention, what I claim as new, and desire to secure by Letters Patent is:—

1. In a typewriter, the combination with a platen carriage, of a type-bar guide positioned normally in front of the platen-carriage and in co-operative relation thereto, said type-bar guide being movable at will into an out-of-service position with respect to said platen carriage.

2. In a typewriter, the combination with a platen carriage, of a pivoted type-bar guide positioned normally in co-operative relation to said platen carriage, said type-bar guide being rotatable at will into an

out-of-service position with respect to the platen carriage, and a ribbon vibrator movable relatively to said type-bar guide, said ribbon vibrator being movable with the type-bar guide into and from the out-of-service position.

3. In a typewriter, the combination with a platen carriage, of a rockable bar positioned substantially parallel to the line of travel of said platen carriage, a type-bar guide carried by said rockable bar, said type-bar guide being normally in co-operative relation to the platen carriage and being movable on an axis afforded by the rocker bar into an out-of-service position with respect to said carriage.

4. In a typewriter, the combination with a platen carriage, of a type-bar guide pivoted for movement into an out-of-service position with respect to said platen carriage, and a ribbon vibrator slidable relatively to said type-bar guide.

5. In a typewriter, the combination with a platen carriage, of type-bar guides, and a ribbon vibrator carried by said type-bar guide, said type-bar guide being mounted for movement relatively to the platen carriage so as to shift the ribbon vibrator into an out-of-service position.

6. In a typewriter, a type bar guide pivotally supported for movement relative to a platen carriage, whereby said guide may be positioned out of operative relation to the platen carriage, a ribbon-vibrator mounted on said type-bar guide for sliding

movement relative thereto, said ribbon-vibrator being movable into and out of operative position by the rotatable movement of the type-bar guide, and means for retaining the guide and the vibrator in their 40 operative and adjusted positions.

7. In a typewriter, a supporting bar pivotally supported in the machine frame, a type-bar guide fixedly secured to said supporting bar, said guide being provided at 45 one end portion with a bifurcated head, said guide being rotatable with the supporting bar whereby the guide may be rotated to a position out of operative relation to a platen carriage, and spring mechanism 50 for retaining the guide in the operative or the adjusted positions thereof.

8. In a typewriter, a supporting bar pivotally supported in the machine frame, a type-bar guide fixedly secured to said supporting bar, a ribbon-vibrator slidably connected to the type-bar guide, said ribbon vibrator being movable independently of said guide and rotatable therewith, and spring mechanism cooperating with the 60 vibrator for retaining the guide and the vibrator in their operative positions and in their adjusted positions.

In testimony whereof I have signed my name to this specification in the presence 65 of two subscribing witnesses.
